UNITED STATES PATENT OFFICE.

OSCAR H. DICKE, OF ROCHESTER, NEW YORK, ASSIGNOR TO GENERAL RAILWAY SIGNAL COMPANY, OF ROCHESTER, NEW YORK.

TRAIN CONTROL.

Application filed July 5, 1924. Serial No. 724,334.

This invention relates to automatic train control systems of the intermittent inductive type, and more particularly to reliable means for transmitting control influences inductively under danger traffic conditions ahead regardless of the speed of the train.

In transmitting control influences inductively from the trackway to a vehicle at selected control points along the track it has been found that current can be induced

in a car-carried coil when cooperating with a trackway device as a result of uni-directional magneto-motive-force in either the car-carried or the trackway device. If this

method is used for transmitting control influences from the trackway to the vehicle, the speed of the vehicle becomes a factor of the value or strength of such control influences; in other words, the potential in-

duced in such coil increases with the speed. Since, however, the time during which a car-carried electro-responsive device may re-

spond to such influence is also dependent on the speed, that is, decreases as the speed in-

creases, a stronger influence is necessary or at least desirable at high speeds than at lower speeds, and for this reason it is desirable to transmit control influences at control points by a method in which the strength of such influence varies directly with the speed.

In applying automatic train control apparatus to railways it is found expedient to transmit a danger influence at the entrance to a caution block, or say, braking

distance in the rear of the exit end of such block corresponding to the entrance to danger territory, and to equip the car-carried apparatus with a suitable delayed action device so that danger traffic conditions are

not fully set up until the train has reached the exit end of such caution block. One well known type of delayed action device is one that is initiated braking distance in

the rear of a danger block, and which gradually sets up more restrictive permissible speed limits so that a minimum speed limit of, say, 15 miles per hour is set up at the end of such block. If a delayed action device of this type is used it is highly im-

portant that the influence communicating means for initiating such device should be effective at all speeds, that is, very low speeds as well as higher speeds, so that it is assured that the train is properly restricted when reaching the exit end of a caution

block regardless of what its speed may have been at the entrance to such block. Influence communicating means of the type heretofore mentioned depend to a certain extent on the speed of the vehicle, and have been found to be ideal for transmitting control influences at average and high train speeds, but have been found inadequate for transmitting control influences at very low speeds.

With the above and other considerations in mind it is proposed in accordance with the present invention to provide an influence communicating means in which the transmission of a control influence depends

upon the induction of voltage in a car-carried coil in response to movement of such coil by a field of flux due to uni-directional magneto-motive-force for initiating a speed

restricting device, and to provide additional means which assures initiation of this speed

restricting device, whether of the delayed type or whether one that immediately becomes effective, which is made active when the train speed is reduced below a certain

predetermined low speed, below which the first mentioned influence communicating means cannot be relied upon for transmitting a control influence, which speed may be taken at say, 3 miles per hour. More

specifically it is proposed to provide a car-carried core having a uni-directional magneto-motive-force induced therein and having a secondary or influence receiving coil associated therewith connected in series with

a stick electro-responsive device which is adapted to drop such stick electro-responsive device if a voltage of a predetermined value is induced therein, and to provide an armature, preferably of the tractive soft iron

type, which if actuated is adapted to de-energize such stick device, provided such armature is actuated when the speed of the train is less than the predetermined value

of 3 miles per hour heretofore assumed; and to equip the trackway with suitable ele-

ments each of which comprises a non-mag-

netized core of magnetic material when in its active condition and has a coil thereon closed in a circuit of low resistance when in its inactive condition.

Other objects, purposes and characteristic features of the present invention will in part be pointed out hereinafter and in part be obvious from the drawings.

In describing the invention in detail reference will be made to the single sheet of drawings in which a very simple type of railway block signal system has been shown, having the trackway apparatus for a train control system embodying the present invention applied thereto; and in which one embodiment of the car-carried apparatus for such a system has been shown conventionally.

Although the present invention has been illustrated in its simplest form, it is desired to be understood that it is not limited to the particular type of system shown; but that many additional features such as, cab signals, provision for operating either pilot or tender first, and other various features which are supplemental rather than basic in a train control system may be added.

Referring to the drawings, the reference character 1 designates track rails divided by insulating joints 2 into blocks, the block I and the adjacent ends of two other blocks H and J being shown. Since the various blocks are assumed to be equipped the same, like parts of each block are designated by like reference characters having distinctive exponents. Although the train control system embodying the present invention may be used without wayside signals, especially if cab signals are used, or may be used with any one of the various types of wayside signals employed in practice, semaphore signals Z only have been shown, and these have been shown conventionally without illustrating their well known operating devices and control circuits. At the exit end of the block I, the direction of traffic being as indicated by the arrow, is provided a suitable source of trackway energy conventionally illustrated by the battery 3 connected in series with the usual adjustable limiting resistance 4, the entrance end of this block having bridged across the track rails thereof a track relay 5, this track relay, in connection with the rails 1 of this block and the trackway source of energy, comprising the usual closed track circuit.

At the entrance end of the block I on the right hand side thereof, when facing the normal direction of traffic, is shown a knock-down or danger control track element T, comprising a U-shaped core 6, preferably constructed of a high grade of laminated magnetic material and terminating in enlarged pole pieces 7. This core 6 is preferably located so that the top of the poles 7 are a few inches above the top of the track rails and is provided with a coil 8, which coil under normal clear traffic conditions ahead is closed in a circuit of low resistance by the front contact 9 of the line or distant relay D. This distant relay D is energized if the block I and the next block in advance thereof are clear, by a circuit in-

cluding front contact 10 of the track relay 5 and front contact 11¹ of the track relay 5¹.

At the exit end of the block I and on the left hand side of the trackway are provided two trackway devices RP and RS 70 similar to the knock-down track element T. These trackway devices RS and RP have their coils 14 and 15 connected in series through a front contact 16¹ of the track relay 5¹ under clear traffic conditions ahead, 75 and are adapted to transmit a resetting impulse by the, so-called, "transformer reset scheme", when the block ahead is unoccupied. By looking at the drawings it will be noted that the track elements T are active when 80 either the block at the entrance to which they are placed, or the next block in advance thereof, are occupied, by opening of the contact 9, and that the reset elements RS and RP are active, that is, connected 85 in a closed circuit, providing the block in advance thereof is unoccupied; also, that the knock-down element T is active when its control circuit is opened, thus being on the closed circuit principle, and that the reset elements RS and RP are active when their circuit is closed, thus being controlled on the open circuit principle. This is, of course, desirable so that a false opening of the circuit controlling the track element T changes 90 it to its active condition and a false opening of the circuit controlling the reset device places it in its inactive condition, thus causing 95 both the knock-down and the reset apparatus to function on the side of safety.

On the railway vehicle, which has been conventionally shown by wheels and axles 18 and 19, are provided an influence receiving knock-down car element L, located on the right hand side thereof, and a pair of reset elements KP and KS, forming parts of the transformer reset scheme heretofore mentioned. The car element L comprises an inverted U-shaped core 20, terminating in enlarged pole pieces 21 which are located a 105 distance above the track, so as to cooperate with the core 6 of the track element T through an air gap of, say, 1 to 2½ inches. This core 20 has an air gap therein in which is contained an armature 22 preferably of 110 the tractive soft iron type having a contact 23 connected thereto but insulated therefrom, as shown. This armature 22 is preferably constructed so as not to increase the reluctance of the core 20 appreciably and also so as not to respond to jars and vibrations of the element L. The reset car elements KP and KS each comprise inverted U-shaped cores 24 and 25 having coils 26 and 27 respectively contained thereon, the coils 115 26 and 27 respectively being connected in series so that the turns of these coils link the core in the same direction.

On the car are provided a control relay CR and a reset relay RS which have for 120

convenience been shown conventionally. In practice these relays are substantially constructed and have well-balanced armatures supported about vertical axes so as not to respond to jars and vibrations to which they are necessarily subjected in practice. These relays are adapted to control a permissive speed device of the delayed action type, and for convenience only one type of delayed action device has been shown, namely, one of the type which is delayed in accordance with the progress of a vehicle along the track. Since the present invention does not relate to any specific form of delayed action device one of the type shown in the application of Winthrop K. Howe, Ser. No. 38,132 filed July 6, 1915, has been illustrated and will be very briefly described.

This delayed or retarded cam mechanism includes a centrifugal device C comprising a shaft 30 driven from the axle 18 or 19 in any suitable manner and having a grooved collar 31 slidably contained thereon, which is adapted to be moved up and down in response to the speed of the vehicle by reason of centrifugal force acting on the fly balls 32 through links 33 and against the tension of the compression spring 34 contained on this shaft 30. Adjacent the centrifugal device C is suitably mounted a speed shaft 35 having a cam 36 and an angle lever 37 fixedly secured thereto. The angle lever 37 has one of its legs bifurcated and engaging the groove of the collar 31 and has pivotally secured to the extreme end of the other arm a floating lever 38 by a pin 39. The free end of this floating lever 38 is bifurcated and contains a roller 40 bearing against the cam surface of a cam 41 pinned to the cam shaft 42 rotatably supported in any suitable manner. This cam shaft 42 is biased to its normal position by a spring 43 connected to the free end of an arm 44 fastened to and projecting from this shaft 42.

It will be noted that any intermediate point of the floating lever 38 responds in its movement to both the position of the cam 41 and the speed of the train as manifested by the speed responsive device C, and all that is necessary to determine when the speed of the train is excessive for various positions of the cam 41 is to actuate suitable means connected to an intermediate point of this floating lever 38. In the particular arrangement shown, a link 49 has one end pivotally secured to an intermediate point of the floating lever 38, and has its other end pivotally connected to an eccentrically located pin on a sector 54 journaled on a pin 55. This sector 54 is biased in a counter-clockwise direction by a spring 70 which in turn urges the roller 40 against the cam 41. The sector 54 is shaped to form a cam having a depressed or cut-away portion against which a roller 72 connected to a spring finger

73 is adapted to ride, so that if this sector 54 is moved in a clockwise direction to a predetermined extent from its normal position, the contact 73 separates from the contact 74, so that a suitable circuit may be interrupted when the speed of the train is excessive.

On the cam shaft 42 is also secured a worm wheel 45 having a mutilated portion 46. This mutilated gear 45 is adapted to be rotated in one direction or the other, depending on the direction of the movement of the vehicle, by a worm 47 pinned to a shaft 48 driven from the wheels of the vehicle in any suitable manner under predetermined conditions of the apparatus. Under normal clear traffic conditions of the car-carried apparatus this worm 47 is held out of meshed relation with the worm wheel 45 by the cam starter magnet CS, which has a core 50 pivotally secured to a block 51 in which the shaft 48 is journaled. This block 51 is biased downwardly by a spring 52 having its other end secured to a lug 53, so that if the cam starter magnet CS is de-energized, the spring 52, together with gravity acting on these devices, causes the worm 47 to engage the worm wheel 45, the shaft 48 being preferably driven through a universal connection from the wheels of the vehicle so that it may be freely moved up and down by the cam starter magnet CS.

Since the present invention does not relate to any particular type of brake setting device, an electro-pneumatic valve EPV has for convenience been shown conventionally for this purpose. This valve EPV may control suitable means for actuating the usual engineer's brake valve in a manner so that the engineer cannot prevent an automatic brake application when this device EPV is deenergized, may operate a suitable brake applying device which vents the brake pipe and cuts off main reservoir pressure from the engineer's brake valve when actuated so that he may not recharge the brake pipe, or may control some other type of brake applying device.

Under normal conditions of the apparatus, corresponding to clear traffic conditions ahead, the control relay CR is energized by a stick circuit including its front contact 60 and the secondary coil S of the car element L as follows:—beginning at the battery 56, wire 57, winding of the control relay CR, wires 58 and 59, front contact 60 of the control relay CR, wires 61, 62 and 63, contact 23 of the car element L, wires 64 and 65, secondary coil S of the car element L, wire 66, back to the battery 56. The battery 56 maintains the control relay CR energized sufficiently to just maintain it up under normal conditions and without appreciably magnetizing the core of the car element L. It should be noted that the contact 23 of the car element

L included in this circuit is shunted by a partial circuit comprising, wire 67, speed contact 68 and wire 69. The speed contact 68 has a roller 75 pivotally fastened thereto which engages the speed cam 36, so that this contact is opened when and so long as the speed of the train is less than, say, 3 miles per hour.

The primary coil P of the car element L 10 is the flux producing coil for this element L, and since the presence of flux of a predetermined amount is an essential requisite to the reliable functioning of this car element this primary coil P is energized by a circuit 15 including the brake applying device EPV, so that interruption of this circuit or depreciation of current flowing in this circuit below a certain value causes dropping of the device EPV and effects an automatic application 20 of the brakes. This circuit may be traced as follows:—beginning at the terminal B of a suitable source of direct current such as a battery, wire 78, winding of the EPV, wire 79, cam governing contacts 74 and 73, wire 80, primary coil P, wire 81 back to a common return wire C connected to the other terminal of such battery. With the control relay CR 25 energized the cam starter magnet CS is energized through a circuit including the front contact 82 of the control relay CR, which circuit may readily be traced in the drawings.

Operation.—By looking at the car-carried 30 influence receiving elements and the track-way influence transmitting elements, it will be noted that the pair of reset elements is encountered first as the train is just about to enter a block, after which the single knock-down or danger control elements comes into 35 communicating relationship. This arrangement is employed, so that when a train is passing through a caution block and it again enters an unoccupied caution block the delayed action device may be restored and again initiated, thereby allowing the train to proceed the same as though it were entering a caution block for the first time, that is, a caution block following a clear block.

Let us assume that a train is moving 40 through the block H in the direction of the arrow when the block J in advance thereof is occupied by another train. Under this condition the track relay 51 is in its de-energized 45 position and has its front contact 11' in the lower position so as to de-energize the relay D at the entrance to the block I, which in turn puts the coil 8 of the track element T in an open circuit and makes this element 50 active. Let us assume that the train is just about to enter a caution block I and passes by the track element T at a speed above 3 miles per hour, that is, with the contact 68 closed. As the car element L passes over the 55 track element T a rapid increase of flux

through the secondary coil S takes place; this is primarily due to the decrease of reluctance of the magnetic circuit including the elements L and T and is to a certain extent, it is believed, due to a diversion of flux from leakage paths surrounding the primary coil P, and to a certain extent to the increase of the total flux passing through this primary coil P.

This rapid increase of flux in the secondary coils S induces a voltage in the circuit including the control relay CR and the battery 56 which by reason of the manner in which the coils are connected is in a direction to oppose the voltage of the battery 56 60 and is of a value sufficient to de-energize the control relay CR. With the control relay CR once in its de-energized position and its front contact 60 opened, thereby interrupting its stick circuit, the relay CR is permanently de-energized. As the train proceeds and the car element L recedes from the track element T, and this increased flux again decreases to its normal value, a voltage is induced in the opposite direction in this coil, which voltage is of no avail since the stick circuit has been interrupted. Dropping of the control relay CR causes de-energization 65 of the cam starter magnet CS, thus causing the worm 47 to engage worm wheel 45 and in turn causing gradual rotation of the cam 41, thereby setting up more restrictive speed limits as the train proceeds through the block. It is of course understood that, if the speed of the train is above the permissive speed limit set up by the cam 41, the angle lever 37, floating lever 38, link 49 and sector 54 co-operate to interrupt the energizing circuit for the device EPV. As the train reaches the end of the block I, this cam 41 70 will have assumed its ultimate position and restricted the speed to that desired to be enforced in an occupied block, which for convenience may be assumed to be 15 miles per hour.

Let us now assume that the train is moving 75 in the block I with its cam initiated as just explained, but that said another train formerly occupying the block J has passed out of this block. As the train in question is just about to enter the block J and a short distance before the car element L registers with the track element T, the car-carried reset elements KS and KP register with the reset track devices RP and RS. As heretofore mentioned, this reset arrangement is conveniently called the "transformer scheme", this term is preferably used because the car element KP in combination with the track element RS may be said to comprise one transformer, and the track element RP in combination with the car-carried element KS may be said to comprise another transformer in which the letters P and S designate primary and secondary coils of 80

such transformers respectively. In any event, if the reset car element KP passes by the track element RS when the contact 16¹ is closed, which is true when the block J is clear as has been assumed, a current is induced in the secondary winding 14 by reason of flux produced by the car element KP which has its coils 27 connected to a suitable source of direct current as indicated by the letters B and C. This current induced in the winding 14 of the track element RS causes a rapid building up of flux in the track element RP, and this rapid increase of flux in the track element RP, and the rapid change of flux by reason of registration of the car element KS therewith and specially due to decrease of the reluctance of the magnetic circuit including the elements RP and KS and the movement of the element KS by the track element RP, induces a voltage in the coils 26 of the car element KS, which in turn causes a current to flow in the reset relay RS, thereby closing its front contact 83 and closing a pick up circuit for the control relay CR which is the same as its stick circuit except that its front contact 60 is shunted by the contact 83 of the reset relay RS. With this control relay CR once picked up, it will remain energized by its stick circuit including the battery 56, so that dropping of the reset relay RS, which occurs as soon as the reset devices are out of registration will not affect this relay CR.

As thus far described it is understood that the cam starter magnet CS is de-energized each time that a train enters a caution or danger block and is again re-energized when it approaches either a caution or a clear block, so that, if a train has passed through a caution block and again enters a caution block, the cam starter magnet CS is momentarily energized and again de-energized upon entering such caution block, so that the cam is reset and may again run down in such caution block; also, that if a train passes through a caution block and then enters a danger block, the cam will remain in its ultimate run down position and thereafter enforce the minimum speed limit of 15 miles per hour heretofore mentioned.

Let us now assume that the train is passing from one clear block into another clear block under which conditions the track element T and also the pair of reset track elements RP and RS are in their normal closed circuit condition. As the train passes by a reset point so that the elements KS and KP register with track elements RP and RS the reset relay RS is momentarily picked up without producing any material effect upon the car-carried apparatus, because the control relay CR is already energized. As the car element L passes by the track element T under the assumed condition, insufficient

voltage is induced in the secondary coil S to drop the control relay CR, regardless of the speed of the train; this, it is believed, is due to the fact that the coil 8 of the track element T acts as a bucking coil, so to speak, and allows insufficient flux to pass through the core 6 of this track element to materially effect the distribution of magnetic flux about the car element L. In other words, as the car element L gets into registration with the track element T a very small amount of flux passing through this track element T sets up a large current in the coil 8, which current flows in a direction to oppose a further increase of flux, so that eventually a rather small amount of flux actually passes through the track element T, thus effecting a similar increase of flux through the secondary coil S of the car element this change of flux, however, being insufficient to drop the control relay CR. Net, under clear traffic conditions the track element T produces no effect on the car-carried apparatus as far as its action upon the control relay CR is concerned.

As heretofore mentioned, the induction or potential in a car-carried coil by reason of a change of flux due to a constant magneto-motive-force and movement of the vehicle is not suitable to transmit control influences at extremely low speeds. To explain, let us assume that the primary coil P of the car element L is energized to a degree to produce a magneto-motive-force which is just a trifle less than that which is capable of dropping the control relay CR when the car passes a track element T in its inactive or short circuited condition when the train is moving at the speed at which the influence communicating means functions the best, which in practice has been found to be somewhere between 20 and 50 miles per hour. With the primary coil P energized to this extent insufficient potential is induced in the secondary coil S of the car element L when the car passes a track element T having its coil open circuited, that is an active element, at speeds less than say, 2½ to 3 miles per hour. In other words, the speed range through which the influence communicating means may effectively be made active or inactive respectively, depending on whether its coil is open or closed circuited, may extend only from say 2½ miles per hour upwards.

When the speed of the train is below a value at which the secondary coil S cannot be relied on to transmit the control influence which speed may be assumed to be 3 miles per hour, the speed cam 36 assumes a position so that the roller 75 rides onto the peak of this cam 36, thereby opening the contact 68 and keeping it open so long as the speed remains below this low value, so that the contact 23 is no longer shunted and if opened drops the relay CR. As the car element L passes

over the track element T having its coil open-circuited, or even if it stands over such element, the magnetic circuit for the tractive armature 22 and including the trackway core 6 has such little reluctance that enough magnetism passes through the armature 22 so as to attract the same, whereby the contact 23 is opened and the control relay CR is de-energized; so that the control relay CR is de-energized when a train enters a caution block 10 regardless of the speed of the train at the time of registration of elements L and T. It may be stated at this time that the control relay CR also is de-energized when the train enters a clear block at an extremely low speed, because the bucking coil 8 at such speed or certainly at stand still is unable to buck back the flux so that armature 22 is operated. Although this may at times unnecessarily de-energize the control relay CR, the engineer in practice is not required to go by a control point at less than 3 miles per hour, and if he does this unnecessarily, he may be justifiably penalized. Such penalty will induce him to thereafter avoid reducing his speed below this value when passing a track element T under clear traffic conditions.

A train control system has thus been devised in which control influences are transmitted inductively in a manner so that the value or strength of such influence increases with the speed of the train, which is desirable on account of the shorter period of time 35 through which an influence may be transmitted by such track elements at the higher speeds, and in which the transmission of a control influence at extremely low speeds is accomplished by means responsive to the 40 speed of the train, and a contact responsive at extremely low speeds and when a vehicle stands still with the influence transmitting elements in registration, whereby a speed restricting device, whether retarded or immediately effective, and one which continues 45 to be effective so long as no clearing influence is transmitted from the trackway, may be used to limit the speed of the train.

Having thus shown and described one 50 rather specific embodiment of the invention, it is desired to have it understood that this has been done for illustrative purposes rather than for the purpose of limiting the scope of the invention, and that various changes, modifications and additions may be made to adapt the invention to the particular type of system in connection with which it is to be used. Also it is to be understood that suitable expedients may be used to 55 guard against jars and vibrations both as to the car elements as a whole and the armature 22 associated with the car element L, all without departing from the scope of 60 the present invention or the idea of means 65 underlying the same.

What is desired to be secured by Letters Patent of the United States is:—

1. In an automatic train control system; the combination of car-carried apparatus comprising, a permissive speed device which 70 normally assumes a certain high permissive speed condition, which if initiated gradually assumes more restricted speed conditions, and which applies the brakes of the train if the actual speed of the vehicle exceeds the permissive speed set up by this device, a normally energized electrically operated stick device for maintaining said permissive speed device in its normal condition, an inductive influence receiving coil connected in the stick circuit of said stick device adapted to impress a voltage in said circuit when inductively influenced by passing an inductive trackway device and thereby drop said stick device, and other means for 85 dropping said stick device when the speed of the train is reduced below a certain value; and of trackway means for inductively influencing said coil.

2. An automatic train control system comprising, vehicle-carried apparatus including a brake setting device, a permissive speed device normally setting up a certain permissive speed and which if initiated gradually sets up more restrictive speed limits, an actual 90 speed device, means for actuating said brake setting device if the actual speed of the vehicle exceeds the permissive speed set up by this device, and means partly on the vehicle and partly along the trackway for automatically initiating said permissive speed device so as to set up lower permissive speed limits under danger traffic conditions ahead regardless of the speed of the train and including a vehicle-carried tractive armature responsive to flux linking car-carried and trackway devices and responsive at extremely low speeds and at zero speed, and a coil located in inductive relation with the trackway responsive at higher speeds.

3. An automatic train control system comprising, vehicle-carried apparatus including a brake setting device, a permissive speed device normally setting up a certain permissive speed and if initiated gradually setting 115 up more restrictive speed limits, an actual speed device, means for actuating said brake setting device if the actual speed of the vehicle exceeds the permissive speed set up by this device, and means partly on the vehicle and partly along the trackway for initiating said permissive speed device so as to reduce the permissive speed of the train comprising two distinctive devices one of which depends for its operation on magnetic flux alone and 120 the other of which depends for its operation on both magnetic flux and movement of the vehicle.

4. An automatic train control system comprising, a permissive speed device changed 130

in accordance with the progress of the vehicle along the trackway when initiated and gradually setting up lower permissive speed limits in accordance with such progress, means

5 for applying the brakes of the usual air brake system of the train actuated if the speed of the vehicle exceeds the permissive speed set up by this permissive speed device, and means partly on the vehicle and partly 10 along the trackway including a source of unidirectional magneto-motive-force and acting through an intervening air-gap for initiating said permissive speed device effective at all speeds under danger traffic conditions ahead 15 and including a stationary inert trackway device which does not require any trackway source of energy.

5. An automatic train control system comprising, a permission speed device changed in accordance with the progress of the vehicle along the trackway when initiated and gradually setting up lower permission speed limits with such progress, means for applying the brakes of the usual air brake system of the train actuated if the speed of the vehicle exceeds the permissive speed set up by this permissive speed device, means partly on the vehicle and partly along the trackway for initiating said permissive speed device under 25 danger traffic conditions ahead effective by electro-magnetic induction at certain speeds and by magnetic induction at other speeds, said last mentioned means including only inert trackway devices which do not require 30 trackway energy.

6. An automatic train control system comprising, a permissive speed device changed in accordance with the progress of the vehicle along the trackway when initiated and gradually setting up lower permissive speed limits with such progress, means for applying the brakes of the usual air brake system of the train actuated if the speed of the vehicle exceeds the permissive speed set up by this permissive speed device, initiating means partly on the vehicle and partly along the trackway and acting through an intervening air-gap for initiating said permissive speed device and effective at all speeds 45 under danger traffic conditions ahead due to the combined action of magnetic and electro-magnetic induction, said initiating means including an inert trackway device which does not require any trackway source of energy, 50 and means partly on the vehicle and partly along the trackway for restoring said permissive speed device to normal active only under clear traffic conditions ahead, said restoring means including inert trackway influence 55 communicating apparatus requiring no trackway energy.

7. An automatic train control system comprising, a permissive speed device, an actual speed device, a brake setting device, and means for initiating said permissive speed

device located partly on the vehicle and partly along the trackway and including a car-carried coil adapted to have a voltage induced therein to initiate said permissive speed device due to a change of magnetic flux dependent on the speed of the vehicle, and other means for initiating said permissive speed device responsive to the amount of flux and not the rate of change of flux and effective if the speed is reduced below a certain 75 value.

8. An automatic train control system of the intermittent type comprising; train-carried apparatus for restricting the progress of the train; inductive influence communicating means partly on the vehicle and partly along the trackway for rendering said apparatus effective; and other means for rendering said apparatus effective, actuated when the speed of the train is less than a certain 80 value.

9. In an automatic train control system; the combination of car-carried apparatus comprising, a permissive speed device which when active steps up a predetermined low permissive speed limit; a normally energized electrically operated stick device for maintaining said permissive speed device inactive, means for applying the brakes of the train if the actual speed of the train exceeds the permissive speed, an inductive influence receiving coil connected in the stick circuit of said stick device adapted to impress a voltage in said circuit when inductively influenced by passing an inductive trackway device and thereby drop said stick device, and other means for dropping said stick device when the speed of the train is reduced below a certain value; and of trackway means for inductively influencing said coil.

10. An automatic train control system comprising, a permissive speed device, an actual speed device, a brake setting device, and means for initiating said permissive speed device located partly on the vehicle and partly along the trackway and including a car-carried coil adapted to have a voltage induced therein to initiate said permissive speed device due to a change of magnetic flux dependent on the speed of the vehicle, and other means for initiating said permissive speed device which is responsive to flux irrespective of the rate of change of such flux.

11. An automatic train control system of the intermittent inductive type comprising, a brake control device rendered active if the train exceeds a predetermined permissive speed limit, and two separate means inductively actuated from the trackway for establishing such speed limit, one of said means being responsive to the rate of change of flux and the other being responsive to flux irrespective of its rate of change.

12. An automatic train control system of the intermittent inductive type comprising,

a brake control device rendered active if the train exceeds a predetermined permissive speed limit, two separate means inductively actuated from the trackway for establishing such speed limit, one of said means being responsive to the rate of change of flux and the other being responsive to flux irrespective of its rate of change, and separate means also inductively actuated from the trackway and effective under favorable traffic conditions only for discontinuing the imposition of that established speed limit.

13. Influence communicating means for automatic train control systems of the inductive non-physical contact type comprising; car-carried apparatus including a U-shaped core having a normally energized primary coil, a secondary coil and a movable armature associated therewith; and a train control device controlled by a circuit including a contact operated by said armature and said secondary coil in series.

14. Influence communicating means for automatic train control systems of the inductive non-physical contact type comprising; car-carried apparatus including a U-shaped core having a normally energized primary coil, a secondary coil and a movable armature associated therewith; and a stick electro-responsive train control device having a stick contact associated therewith and normally energized by a circuit including a contact operated by said armature, a source of direct current, said secondary coil and said stick contact in series.

15. Influence communicating means according to claim 14, having means associated therewith for shunting the contact operated by said armature when the speed of the car is above a certain value.

16. Influence communicating means for automatic train control systems of the inductive non-physical contact type comprising; car-carried apparatus including a U-shaped core having a primary coil, a secondary coil and a movable armature associated therewith; a stick electro-responsive train control device having a stick contact associated therewith and normally energized by a circuit including a contact operated by said armature, a source of direct current, said secondary coil and said stick contact in series, and a trackway device for bridging said core upon the passage of a car thereby which trackway device comprises an inert core of magnetic material.

17. Influence communicating means for automatic train control systems of the inductive non-physical contact type comprising; car-carried apparatus including a U-shaped core having a primary coil, a secondary coil and a movable armature associated therewith; a stick electro-responsive train control

device having a stick contact associated therewith and normally energized by a circuit including a contact operated by said armature, a source of direct current, said secondary coil and said stick contact in series; and a trackway device for bridging said car-carried core upon the passage of the car thereby including a core having a winding thereon which winding is contained in a closed circuit under favorable traffic conditions ahead.

18. Influence communicating means for automatic train control systems of the inductive non-physical contact type comprising; car-carried apparatus including a U-shaped core having a constantly energized primary coil, a secondary coil and a movable armature associated therewith; a stick electro-responsive train control device having a stick contact associated therewith normally energized by a circuit including a contact operated by said armature, said secondary coil and said stick contact in series; and a trackway device for bridging said core upon passage of the car-carried core thereby including a core having a winding thereon closed in a de-energized circuit of low resistance under favorable traffic conditions ahead and open-circuited under unfavorable traffic conditions ahead.

19. Influence communicating means for automatic train control systems of the inductive non-physical contact type comprising; car-carried apparatus including a U-shaped core having a constantly energized primary coil, a secondary coil and a movable armature associated therewith; a direct current source of energy for energizing said primary coil; a stick relay; and a circuit including a source of direct current, a front contact of said stick relay, a contact operated by said armature and said secondary coil in series.

20. An automatic train control system comprising, a brake control device; speed control means which if active causes the brake control device to become active and effect a brake application if a predetermined speed limit is exceeded; and means for rendering said speed control means active comprising; a stick relay normally energized by a circuit including a normally closed contact of said stick relay and an influence receiving coil in which a voltage may be induced by suitable trackway means upon passage of the train by such trackway means so as to effect de-energization of said stick relay, and supplemental means for de-energizing said stick relay rendered active if the speed of the train is less than a certain value and upon passage of the train by suitable trackway means.

In testimony whereof I affix my signature.

OSCAR H. DICKE.
